(57) **CLAIM**

The ornamental design for an Adinkra alphabet as shown and described.

DESCRIPTION

FIG. 1 is a face view of an Adinkra alphabet, showing the claimed design.

FIG. 2 is a face view of an Adinkra alphabet with environmental structure shown in broken lines and forming no part of the claimed design; and,

FIGS. 3-47 show characters separate of the alphabet shown in its entirety in FIG. 1, and in an enlarged state, for clarity of illustration.
